UNITED STATES PATENT OFFICE.

MICHAEL McCANN, OF GLENMORRIS, NEW YORK, ASSIGNOR TO FREDERICK OSANN COMPANY, OF NEW YORK, N. Y., A CORPORATION OF NEW YORK.

BUTTONHOLE-CUTTER MECHANISM.

Application filed June 8, 1922. Serial No. 566,784.

To all whom it may concern:

Be it known that I, MICHAEL McCANN, a citizen of the United States of America, residing in Glenmorris, L. I., in the county of 5 Queens and State of New York, have invented certain new and useful Improvements in Buttonhole-Cutter Mechanism, of which the following is a true and exact description, reference being had to the accompanying 10 drawings, which form a part thereof.

My invention relates to button hole sewing machines and has for its object to provide a button hole cutter and means for actuating the cutter so interrelated and combined with the stop mechanism as to insure 15 not only the correct operation of the knife at the end of the machine cycle but also the withdrawal of the button hole cutting knife to non-operative position before the machine is started for a new button hole sewing cycle.

The nature of my improvements will be best understood as described in connection 20 with the drawings which illustrate my improvement as embodied in a button hole sewing machine mechanism of the general character described in my pending application for Letters Patent, Serial No. 325,710 filed 23 September, 1919.

In the drawings:

Figure 1 is a side elevation of the button hole sewing machine with the side plates of the upper arm head removed and the side of the lower casing cut away and with certain parts of the machine, having no direct bearing on my present invention, omitted.

Figure 2 is a plan view of the machine taken as on the line 2—2 of Fig. 1, and showing certain details of the mechanism omitting in Fig. 1.

Figure 3 is a sectional elevation taken on the line 3—3 of Fig. 1.

Figure 4, a sectional elevation taken on the line 4—4 of Fig. 1.

Figure 5 is a view showing parts of the mechanism shown in Figs. 2 and 4 in the positions they occupy at the instant when the knife actuating clutch is thrown into engagement.

Figure 6 is a view of the parts shown in the lower part of Fig. 4 in the positions they occupy at the instant when the clutch is engaged.

Figure 7 is a view similar to Fig. 6, showing the position of the parts at the period

in the cycle of the machine when the cutter has made its downward stroke to cut a button hole.

Figure 8 is a plan view showing the position of the parts shown in Fig. 5 at the period in the cycle of the machine corresponding to that shown in Fig. 7.

Figure 9 is a view similar to Fig. 8 with the parts in the position they occupy when the machine is stopped.

Figure 10 is a view of the same parts shown in Fig. 9 in the position they occupy during the retraction of the stop mechanism and immediately before the full retraction of the stop mechanism.

Figure 11 is a side view taken on the line 11—11 of Fig. 9.

Figure 12 is a sectional view taken on the line 12—12 of Fig. 2, showing a certain detail of the machine, and

Figure 13 is a side elevation showing the bell crank lever used in the starting of the machine.

A indicates the casing enclosing the lower part of the sewing machine mechanism; A' the hollow vertical arm of the machine; A², the horizontal upper arm of the machine and A³ the head of the machine, the upper horizontal portion of the casing A, making up the table of the machine, has an opening indicated at B which gives clearance to a certain part of the feed actuating mechanism, and another opening at B' for the passage of the needles. C and C' indicate downwardly extending webs of the casing A which serve as supports for certain parts of the machine, and C² is also a downwardly extending portion of the casing A which serves as a bearing for the shaft indicated at F'. D is the main driving shaft of the machine the end of which, which extends beyond the right hand end of the casing, has attached to it the stop disc D² having a braking surface D³ formed on or attached to its face and a stop recess D⁴ extending from its face inward as shown. D⁵ is the fast pulley attached to the disc D² and D⁶ the loose pulley. D⁷ is an eccentric secured to the shaft D; D⁸ a gear wheel secured to said shaft; D⁹ a cam secured to the shaft D and having an annular head D¹⁰ which extends beyond the lower portion of the cam, as shown in Fig. 12. D¹¹ indicates, although not in detail, an eccentric secured on the shaft D and through it the cam shaft, to be described, is actuated.

D¹² is a cam secured on the shaft D and through it motion is given to a certain part of the machine not directly connected with my present invention.

5 E is an eccentric rod actuated by the eccentric D⁷ and connected at its upper end through a lever arm E' with a rock shaft E² which through certain mechanism, the position of which is indicated at E³, gives a reciprocating movement to the needle bar E⁴ carrying at its lower end the needles E⁵.

F is a gear wheel engaged with and driven by the gear wheel D⁸ on the shaft D and attached to the shaft F' to the other end of which shaft is attached a cam connected at F². This cam gives a rocking motion to a block F³ through engagement with the forked lower end F⁴ of this block which is pivoted at F⁵ and is formed with a slot bearing for a slide block.

G is a rock shaft in the upper arm of the machine having at its left hand end a lever arm G' supporting a guideway G² in which the needle bar E⁴ moves. G³ is a lever arm secured to the right hand end of the rock shaft G having a curved lower end G⁴ by which it is connected to the lever arm H, to be described, said lever G³ being formed with the slide block slot G⁵ which in the position of the machine indicated, for instance, in Fig. 3, registers with the slide block slot in the block F³; the connection of the arm G⁴ of the lever G³ with the lever H is made, as indicated in Fig. 3, through a slide block and the lever H is attached to a rock shaft H' which at its left hand end is provided with a lever arm H² connected to a shaft H³ to which are attached the loopers H⁴ and which is given a rocking motion in proper timing with the operation of the needles by a mechanism indicated, though not in detail, at H⁵, such mechanism having no direct connection with my present invention.

45 I is a cam shaft seated in the lower part of the machine and actuated by the eccentric device indicated at D¹¹ through an eccentric rod I' and a ratchet actuating clutch indicated, though not in detail, at I², I³ indicating a clutch the function of which is to hold the shaft I stationary between the intermittent periods of motion given to it by the eccentric actuated clutch I². I⁴ is a cam secured on the shaft I and by means of which motion is given to the feed mechanism of the machine. I⁵ is a disc secured on the shaft I and I⁶ a cam also secured on the shaft I and having formed on its face the cam curve indicated in Fig. 3. The disc I⁵ which perhaps should be referred to as a cam, is provided with an adjustable finger I⁷ and with a recess indicated at I⁸ and extending inward from the left hand side of the disc as best indicated perhaps in Fig. 1.

60 J is a pivoted lever to which reciprocating motion is given by the cam I⁴, see Figs. 1 and 2, and in the curved upper surface of which is the adjustable slide block indicated at J', said slide block being connected with the feed mechanism partially indicated at J².

ing motion is given by the cam I⁴, see Figs. 1 and 2, and in the curved upper surface of which is the adjustable slide block indicated at J', said slide block being connected with the feed mechanism partially indicated at J².

5 K is a lever pivoted at K', see Fig. 3, having a cam roller K² projecting from it into the cam I⁶ and connected through a rod K³ with a lever K⁴ pivoted at K⁵, the connection being made through the slot K⁶ of said lever and said lever carrying at its free end slide blocks, one moving in the slot G⁵ of the lever G³ and the other in the corresponding slot in the pivoted block F³.

10 L is a rock shaft extending from the upper arm of the machine and connected by mechanism indicated at L' with a reciprocating rod L² guided in the head of the machine and carrying at its lower end the knife L³ for cutting the button hole. L⁴ is a lever arm attached to the shaft L and connected through a pin L⁵ with a link L⁶ pivotally connected at its upper end to a lever arm L⁷ attached to a longitudinally movable clutch member L⁸ which slides on the rock shaft E² and is engageable with a clutch member L⁹ permanently attached to said shaft.

15 M is a longitudinally movable shaft for actuating the stop motion of the belt shifter. To its right hand end is attached the forked lever M' to one arm of which is secured the stop finger M² and also attached to the right hand end of the shaft M is the belt shifter M³, m³ indicating the belt. M⁴ and M⁵ are buffer pads secured to the shaft M and limiting its travel in both directions. M⁶ is an arm secured to the right hand end of the shaft M and carrying the thread cutter indicated at M⁷. M⁸ is a spring acting to press the shaft M toward the right and M⁹, see Figs 2 and 13, a lever which in practice is connected with a treadle and by which the shaft M is moved toward the left when it is desired to start the machine. Pivotally connected to the shaft M is the locking bar N having projecting upward from its upper face the adjustable, latch locking pin indicated at N', the free end N² of the locking bar or of an extension from the locking bar extends to a position where in certain positions of the mechanism it contacts with the edge of the lever P and is notched as indicated at N³ so as to clear the disc I⁵. When the parts are in position shown in Fig. 2 the locking bar N is pressed upward by a spring N⁵ supported on a foot N⁴ secured to the shaft M as shown in Figs. 6 and 7.

20 O is a pivot pin extending downward from the housing of the machine and supporting a locking latch O' which is, as shown, in the form of a bell crank lever normally pressed to operative position by a spring indicated at O².

P is a clutch actuating lever, the upper arm P² of which is engaged with the clutch member L⁸ and which is pivoted in the vertical arm A' of the casing at P'. P³, in Figs. 1 and 4, is a perforation formed in the upper part of the lever P, the lower arm of the lever being formed with a guide slot, as indicated at P⁴, and extending down to a position in which its edge, in the normally operative adjustment of the machine, will contact with the locking bar N, to be described. P⁵ is a pin or roller secured to the lower arm of the lever P and resting during the operation of the machine on the face of the disc I⁵ except when in the revolution of the disc the inlet I⁸ comes into registry with the pin. P⁶ is a slide bar guided on the lever P and with its lower end P⁷ working in the slotted lower end of said lever, the upper end of the slide bar being engaged, through a slot, as indicated in Fig. 4, with the pivot pin L⁶. The length of the slide bar P⁶ is such that when the button hole cutter is in retracted position its lower end is retracted within the forked end P⁴ of the lever but is projected below the end of the lever when the cutter is moved down to cut the button hole. P¹¹ is a spring acting to push the upper arm of the lever P toward the left. P⁸ is a cylinder secured on the end of an arm p⁸ which is attached to the end of the rock shaft L, a spring P⁹ being located in the end of the cylinder and acting to push the locking pin P¹⁰ forward, said pin being arranged to engage the perforation P³ in the lever P when said lever is retracted and the cutter is also in upper retracted position.

Q, see Figs. 2 and 12, is a bar pivotally attached to the shaft M and having, as shown, an edge Q' arranged to contact with the side of the cam D⁹ under conditions to be described, the bar Q having also, as shown, a projecting arm Q² upon which rests the lower end of a rod Q⁴ which rod in the complete machine operates a thread pull-off, not shown, and which forms no part of the invention to which this application substantially relates.

R, see Figs. 1 and 2, is a lever pivoted at R' and engaged through a pin R² to the cam D¹² and pivotally attached to the lever R at R³ is a slide R⁴ moving in a guideway R⁵ to which a lateral reciprocation is imparted by a mechanism, not shown, the slide R⁴ carrying at its end a finger indicated at R⁶ which in my complete machine has to do with the guiding of the loops during certain part of the button hole stitching operation.

To start the machine the stop shaft M is moved toward the left carrying with it the pivoted locking bar N and the pivoted bar Q and the locking bar N during this movement being in its uppermost position its locking pin N', see Figs. 9 and 10, presses against

the beveled end of the latch lock O' and finally engages with the latch lock, as shown in Fig. 2, locking the shaft M and its attachments in the position shown in Fig. 2. During the movement of the locking bar N toward the left its edge contacts with and presses the lower end of the lever P toward the left, moving the upper end of this lever to the right or to the position shown in Fig. 1, in which it moves the clutch member L⁸ out of engagement with the fixed clutch member L⁹ and the rock shaft L being, at the time the machine comes to a stop, in position to retract the knife L³ a pin P¹⁰ connected, as described, to lever arm p⁸ attached to the end of the shaft L will engage in the detent perforation P³ and hold the rock shaft L in fixed position during the stitching of the button hole.

When the stop shaft M is in the position shown in Fig. 2 the belt m³ is on the fast pulley D⁵ and the driving shaft of the machine is put in operation, imparting motion to the rock shaft E², which actuates the needle bar through the described connections, rotating the cam F² on the shaft F' rotating, of course, the cam D⁹ attached to the shaft D and the eccentric indicated at D¹¹ and also rotating, of course, the cam D¹², the function of which is, through the described connections, to actuate the finger R⁶ which, however, having no essential connection with the present invention need not be further described. The rotation of the eccentric attached to the shaft D, as indicated at D¹¹, through the eccentric rod I' and a clutch mechanism actuated by said eccentric rod imparts the step by step movement to the shaft I giving, of course, a step by step movement to the cams attached to said shaft, the cam I⁴ regulating the movement of the feed plate, and the cam I⁶, through the mechanism best shown in Fig. 3, moving the lever K⁴ upward and downward so as to move the slide blocks connected with it, at K', to and away from a point in which their centers will register with the pivot of the block F³, at the same time the rotation of the cam F² on the shaft F' acting on the forked end F⁴ of the block F³ causes the said block to oscillate on its pivot which does not result in any movement of the lever G³ and its attached mechanism when the center of the slide blocks corresponds with the pivoted center of the block but, when the slide blocks are moved upward in the slots, gives a rocking action to the lever G³ which is imparted to the rock shaft G and through it to the needle bar guide G² and is imparted also by the described connections to the rock shaft H' and through it to the sliding shaft H³ to which the loopers H⁴ are attached, the effect being that when the lever G³ is stationary a straight line of stitches is thrown by each needle and when

the lever G^3 is vibrated zig zag stitches of a length determined by the cam path of the cam I^6 are formed by the needles and loopers.

The described interaction of the locking bar N with the clutch actuating lever P by means of which this lever is actuated to disengage the clutch in the act of starting the machine is a feature of my present invention and is of importance because it insures the disengagement of the clutch before the machine starts to sew a button hole and, therefore, insures that the button hole cutter shall not operate after the machine is started and disengagement of the knife actuating mechanism can be equally well assured where a cam is relied upon to effect the disengagement of the clutch.

It will be obvious that the shifting of the lower end of the lever P to the position shown in Fig. 2 disengages the pin P^5 from the notch in the disc I^5 and it will also be obvious that, in locked position, the end of the locking bar is, as is well shown in Fig. 4, in the direct path of the finger I^7 adjustably attached to the disc I^5 . The cycle of the machine in sewing a button hole up to the time when it is desired that the button hole cutter should operate takes place during one rotation of the shaft I and, as the button hole is practically completed, the finger I^7 attached to the disc I^5 comes in contact with the end of the arm N^2 of the locking bar and presses it down as and to the extent indicated in Fig. 6; the downward movement of the locking bar leaving the locking pin N' still engaged with the latch lock O' but clearing the locked end P^4 of the lever P with the result that the spring P^{11} presses the upper end of the lever to the left and presses the loose clutch member L^8 into engagement with the fixed clutch member L^9 and with the further result that, through the mechanism described in connection with Fig. 4, a rocking action is given to the shaft L and, through it, to the cutter which is pressed down to cut the button hole and, will, of course, at once retract it with the following reverse reciprocation of the shaft E^2 . The rocking motion given to the shaft L through the pin L^5 attached to the lever arm L^4 presses down the slide P^6 with the result that its lower end P^7 contacts with and presses down the locking lever N , as shown in Fig. 7, so as to release its locking pin N' from the latch lock O' and, so far as this locking device is concerned, to permit the stop arm M^1 to move toward the right. The actual movement of the locking bar to an extent to effect the stoppage of the machine is, however, in the illustrated construction dependent also on the cam D^9 , that is, the release of the locking bar N , permitting the movement of the stop shaft M toward the right will only completely release the shaft M when the pivot

bar Q is in such relationship to the cam D^9 as to permit this cam to pass under it. At any other time the bar Q contacts with the side of the cam D^9 and holds the stop shaft from completing its movement until the cam has come to its proper position. This cam D^9 not only performs this function in arresting the movement of the stop motion but also lifts the pivot bar Q and through it the rod Q^4 which, as I have stated, actuates a pull off on the upper part of the machine.

When the locking shaft M is released by both locking devices it moves first in the position shown in Fig. 8 where the finger M^2 is in contact with the plate D^3 of the disc D^2 and the projection of the finger on the plate acts as a brake to check the velocity of the machine prior to the registration with the finger M^2 to the stop recess D^4 in the disc D^2 . When this registration occurs the shaft M moves to its furthest right hand position as shown in Fig. 9, the belt shifter M^3 shifting the belt to the loose pulley and the motion of the machine being arrested by the engagement of the finger M^2 in the recess D^4 .

The timing of the machine is such that its motion is arrested at a point in the cycle of movement of its parts when the cutter is fully retracted or, in other words, just as one complete reciprocal rocking movement is given to the shaft L . This, of course, retracts the slide bar P^6 and the complete right hand motion of the shaft M carries the locking bar N from beneath the end of the lever P to the position shown in Fig. 9 and the spring N^6 pushes the locking bar upward to the position shown in Fig. 4 and it will be evident that the clutch is left in engagement when the machine comes to a stop and the clutch actuating lever P in corresponding clutch engaging position.

To re-start the machine the stop shaft M is moved toward the left until the abutment M^4 comes in contact with the frame of the machine, that is, shifted from the position shown in Fig. 9 to that shown in Fig. 2. This withdraws the locking finger M^2 and shifts the belt to the fast pulley. This movement of the shaft M , of course, carries with it the locking bar N which in moving from the position shown in Fig. 9, contacts with the end P^4 of the lever P and shifts it to the position shown in Fig. 2 in which the pin P^5 is completely withdrawn from the recess I^8 in the disc I^5 . This motion of the lever P retracts the loose clutch member L^8 as shown in Fig. 1, and brings the recess P^3 into engagement with the finger P^{10} , as shown in Fig. 1, this engagement preventing any movement of the shaft L and of the cutter actuated by it during the sewing of the button hole.

The movement of the locking bar N to-

wards the left from the position shown in Fig. 9 through the position shown in Fig. 10 to that shown in Fig. 2, results in the engagement of the locking pin N' with the latch lock O' in the manner shown in these drawings and the locking shaft and its connections being thus locked in operative position the machine performs its cycle of operation in sewing a button hole at the end of which the finger V, as already described, contacts with the end N² of the locking lever pressing it down, as shown in Fig. 6, until it releases the lever P which is then actuated by its spring to move the clutch member L⁸ into engagement with the clutch member L⁹ and actuate the cutter as described, the slide bar P⁶ being moved downward simultaneously with the cutter with the result that its end P⁷ pushes the locking bar downward, as shown in Fig. 7, releasing the pin N' from the latch lock and permitting, under the conditions already described, the movement of the stop shaft M to disengage the driving pulley and arrest the movement of the parts. It is sometimes desirable to finish a button hole without cutting it and for this purpose I provide a manually operable device for holding the movable clutch member out of engagement when its actuating mechanism would, at the completion of the button hole, tend to move it to engaging position. As shown, this mechanism consists of a rod T contacting with lever P at T' and ending in a push button T² in the front of the head A³. T³ is a spring holding rod T normally in non-operating position. Obviously, by pressing on the button T² the rod T will press against the lever P and prevent it and its controlled clutch from moving to clutch engaging position. Obviously, also, this device can be used with any mechanism for actuating lever P at proper times.

Having now described my invention, what I claim as new and desire to secure by Letters Patent, is:

1. In a button hole sewing machine comprising a driving shaft, a rock shaft actuated thereby for actuating the needles, a button hole cutter, a rock shaft for actuating the cutter, fixed and movable clutch members on the needle actuating shaft, means for actuating the cutter shaft connected to the movable clutch member and actuated when said movable member is engaged by the fixed member, a longitudinally movable shaft and means actuated thereby for stopping the machine, means for engaging and disengaging the cutter actuating clutch in proper timing with the stopping and starting of the machine consisting of a pivoted lever for shifting the movable clutch member to and from engagement with the fixed member, locking means for holding said lever in retracted position, during the stitching of the button hole and releasing it as said stitching is completed, a latch lock for holding the stop actuating shaft in retracted position, means actuated through the engagement of the clutch member acting to release the latch lock simultaneously with the operation of the cutter and means, actuated by the shifting of the stop actuating shaft to start the machine, for shifting the clutch actuating lever to retracted position.
2. In a button hole sewing machine comprising a driving shaft, a rock shaft actuated thereby for actuating the needles, a button hole cutter, a rock shaft for actuating the cutter, fixed and movable clutch members on the needle actuating shaft, means for actuating the cutter shaft connected to the movable clutch member and actuated when said movable member is engaged by the fixed member, a longitudinally movable shaft and means actuated thereby for stopping the machine, means for engaging and disengaging the cutter actuating clutch in proper timing with the stopping and starting of the machine consisting of a pivoted lever for shifting the movable clutch member to and from engagement with the fixed member, locking means for holding said lever in retracted position, during the stitching of the button hole and releasing it as said stitching is completed, a latch lock for holding the stop actuating shaft in retracted position, means actuated through the engagement of the clutch member acting to release the latch lock simultaneously with the operation of the cutter and means, actuated by the shifting of the stop actuating shaft to start the machine, for shifting the clutch actuating lever to retracted position.
3. In a button hole sewing machine comprising a driving shaft, a rock shaft actuated thereby for actuating the needles, a button hole cutter, a rock shaft for actuating the cutter, fixed and movable clutch members on the needle actuating shaft, means for actuating the cutter shaft connected to the movable clutch member and actuated when said movable member is engaged by the fixed member, a longitudinally movable shaft and means actuated thereby for stopping the machine, means for engaging and disengaging the cutter actuating clutch in proper timing with the stopping and starting of the machine consisting of a pivoted lever for shifting the movable clutch member to and from engagement with the fixed member, locking means for holding said lever in retracted position, during the stitching of the button hole and releasing it as said stitching is completed, a latch lock for holding the stop actuating shaft in retracted position, means actuated through the engagement of the clutch member acting to release the latch lock simultaneously with the operation of the cutter and means, actuated by the shifting of the stop actuating shaft to start the machine, for shifting the clutch actuating lever to retracted position.
4. In a button hole sewing machine com-

prising a driving shaft, a rock shaft actuated thereby for actuating the needles, a button hole cutter, a rock shaft for actuating the cutter, fixed and movable clutch members on the needle actuating shaft, means for actuating the cutter shaft connected to the movable clutch member and actuated when said movable member is engaged by the fixed member, a longitudinally movable shaft and means actuated thereby for stopping the machine, means for engaging and disengaging the cutter actuating clutch in proper timing with the stopping and starting of the machine, consisting of a pivoted lever for shifting the movable clutch member to and from engagement with the fixed member, a locking bar pivotally secured on the stop actuating shaft and held in elevated position by resilient means, said bar and the lower end of the clutch actuating lever being so located that the bar when in elevated position with the stop actuating shaft retracted, contacts with and holds the lever in retracted position and clears and releases the lever when depressed, a latch lock for holding the locking bar and the stop shaft in retracted position constructed as described to release the bar when it is depressed beyond a definite point, means operating in timed relation to the operation of the machine and acting to depress the locking bar to a point where it releases the clutch operating lever and means actuated by the engagement of the clutch members operating to depress the bar further and release it from the lock holding it and the stop shaft against lateral movement.

5. In a button hole sewing machine comprising a driving shaft, a rock shaft actuated thereby for actuating the needles, a button hole cutter, a rock shaft for actuating the cutter, fixed and movable clutch members on the needle actuating shaft, means for actuating the cutter shaft connected to the movable clutch member and actuated when said movable member is engaged by the fixed member, a longitudinally movable shaft and means actuated thereby for stopping the machine, means for engaging and disengaging the cutter actuating clutch in proper timing with the stopping and starting of the machine, consisting of a pivoted lever for shifting the movable clutch member to and from engagement with the fixed member, a locking bar pivotally secured on the stop actuating shaft and held in elevated position by resilient means, said bar and the lower end of the clutch actuating lever being so located that the bar when in elevated position with the stop actuating shaft retracted, contacts with and holds the lever in retracted position and clears and releases the lever when depressed, a latch lock for holding the locking bar and the stop shaft in retracted position constructed as described to release the bar when it is depressed beyond a definite point, a cam moving in timed relation to the stitching of the button hole operating to hold the clutch actuating lever in retracted position and to release it when the clutch is to be engaged said cam having a finger operating on the locking bar to depress it to a point where it will release the clutch operating lever and means actuated by the engagement of the clutch members operating to depress the bar further and release it from the lock holding it and the stop shaft against lateral movement.

6. In a button hole sewing machine of the kind described having a rock shaft for actuating the needles, a second rock shaft for actuating a button hole cutter, fast and loose clutch members on the needle shaft, means whereby the rock cutter shaft is actuated

bar when it is depressed beyond a definite point, means operating in timed relation to the operation of the machine and acting to depress the locking bar to a point where it releases the clutch operating lever, a slide plate guided on the clutch actuating lever and movable thereon between positions in which its lower end is retracted above the lower end of said lever and in which it extends below said lever, said plate being correlated to the lock bar as described and so that when moved downward it depresses the bar to a point where it is released by the latch lock, and means actuated by the clutch when engaged whereby said slide plate is moved downward simultaneously with the operation of the cutter and retracted as the cutter is retracted.

7. In a button hole sewing machine comprising a driving shaft, a rock shaft actuated thereby for actuating the needles, a button hole cutter, a rock shaft for actuating the cutter, fixed and movable clutch members on the needle actuating shaft, means for actuating the cutter shaft connected to the movable clutch member and actuated when said movable member is engaged by the fixed member, a longitudinally movable shaft and means actuated thereby for stopping the machine, means for engaging and disengaging the cutter actuating clutch in proper timing with the stopping and starting of the machine consisting of a pivoted lever for shifting the movable clutch member to and from engagement with the fixed member, a locking bar pivotally secured on the stop actuating shaft and held in elevated position by resilient means, said bar and the lower end of the clutch actuating lever being so located that the bar when in elevated position with the stop actuating shaft retracted, contacts with and holds the lever in retracted position and clears and releases the lever when depressed, a latch lock for holding the locking bar and the stop shaft in retracted position constructed as described to release the bar when it is depressed beyond a definite point, a cam moving in timed relation to the stitching of the button hole operating to hold the clutch actuating lever in retracted position and to release it when the clutch is to be engaged said cam having a finger operating on the locking bar to depress it to a point where it will release the clutch operating lever and means actuated by the engagement of the clutch members operating to depress the bar further and release it from the lock holding it and the stop shaft against lateral movement.

7. In a button hole sewing machine of the kind described having a rock shaft for actuating the needles, a second rock shaft for actuating a button hole cutter, fast and loose clutch members on the needle shaft, means whereby the rock cutter shaft is actuated

- when the clutch members are engaged, a pivoted lever for moving the movable clutch member into and out of engagement and means for actuating said lever in timed relation to the operation of the machine, the device for locking the cutter and its shaft in retracted position consisting of a locking pin secured to the cutter rock shaft and located to engage the clutch actuating lever when it is in retracted position.
8. In a button hole sewing machine comprising a driving shaft, a rock shaft actuated thereby for actuating the needles, a rock shaft for actuating the cutter, fixed and movable clutch members on the needle actuating shaft and means for actuating the cutter shaft connected to the movable clutch member so as to be actuated when the clutch members are engaged:—the mechanism for moving the clutch member which consists of a pivoted lever connected to the clutch at its upper end, a spring acting on said lever to move it into clutch engaging position, means acting on the lower end of said lever to hold it in clutch disengaging position during the stitching of the button hole and to release it as the stitching is completed,
9. In a button hole sewing machine comprising a driving shaft, a rock shaft actuated thereby for actuating the needles, a rock shaft for actuating the cutter, fixed and movable clutch members on the needle actuating shaft and means for actuating the cutter shaft connected to the movable clutch member so as to be actuated when the clutch members are engaged:—the mechanism for moving the clutch member which consists of a pivoted lever connected to the clutch at its upper end, a spring acting on said lever to move it into clutch engaging position, means acting on the lower end of said lever to hold it in clutch disengaging position during the stitching of the button hole and to release it as the stitching is completed, and a push button and rod manually operable from the front of the machine whereby the lever and connected clutch member can be held in inoperative position.

MICHAEL McCANN.
